INVENTOR.

R. L. KURTZ

BY
ATTORNEY.

UNITED STATES PATENT OFFICE.

RAYMOND L. KURTZ, OF DENVER, COLORADO.

DEVICE FOR SECTIONAL CONSTRUCTION.

Application filed September 2, 1924. Serial No. 735,385.

To all whom it may concern:

Be it known that I, RAYMOND L. KURTZ, a citizen of the United States, residing at Denver, in the county of Denver and State of Colorado, have invented certain new and useful Improvements in Devices for Sectional Construction, of which the following is a specification.

This invention relates to a device for the sectional construction of designs and articles for educational, ornamental and useful purposes, and its primary object is to provide a piece of pliable material obliquely slotted with respect to its perimetric edge to interlock or interweave with other similarly constructed pieces for the formation of different articles and designs.

The invention is particularly adapted for use in kindergarten, schools and other educational institutions to develop in a pleasant and diverting manner, the ingenuity and artistic qualities of children by sectional construction and arrangement of various articles and it is a further object of the invention to stimulate the interest and inventive ability of the pupils and to enhance the artistic appearance of the designs and articles produced, by providing sections of the above described character in various colors or by providing the sections with letters, numerals or other symbols which conjunctively may formulate a word or a number or a pictorial or artistic figure of either fanciful or calculated design.

In the accompanying drawings in the several views of which like parts are similarly designated,

Figure 1 represents a face view of one of the sections used in the practice of the invention; in its simplest form;

Figure 2, an edge view of the same;

Figure 3, a face view of a section of modified construction;

Figure 4, an edge view of the section shown in Figure 3;

Figure 5, an assembly of three of the sections shown in Figures 1 and 2, in interlocking relation;

Figure 6, a symmetrical design produced by a different interlocking arrangement of sections of the type shown in Figures 1 and 2;

Figure 7, an assembly of sections of similar character bearing letters arranged to form a word;

Figure 8, an assembly of three sections of the modified construction illustrated in Figures 3 and 4, in interlocked relation;

Figure 9, a different arrangement of sections of similar construction;

Figure 10, an arrangement of a number of sections of the type shown in Figures 3 and 4, in a symmetrical design; and

Figure 11, a modification of the section shown in Figure 3.

In the assembly views sections of different colors have been indicated by shading and it is to be understood that the examples given of the arrangement of the sections are merely illustrative of the method by which the sections are interlocked or interwoven for the formation of designs and useful articles and that their arrangement may be varied to produce other designs and articles of such diversity as to be practically innumerable.

Referring first to Figures 1 and 2, the sections illustrated therein each consist of a piece 5 of thin pliable material, preferably card board, which has one or more slits 6 extending obliquely or at an acute angle from its perimetric edge.

The section as shown is square but it will be evident that it may be made in any other geometrical form or in irregular or arbitrary outline within the spirit and scope of the invention.

The sections are preferably provided with two of the slits at opposite edges and they are interlocked by inserting a slotted edge-portion of one through the slit of another as illustrated in Figure 1, so that the sections are hooked together and may be turned to different positions with relation to each other.

In Figure 5, for example, the middle sec-

tion is disposed at right angles to the outer section while in Figure 7, a number of sections are arranged with their edges in parallel relation to each other.

5 The sections of the last mentioned figure are provided with letters and the sections are so arranged that their letters spell the word "schools".

It will be seen that in this manner the 10 pupils are taught the rudiments of word construction at the same time that their artistic sense is developed by the symmetrical arrangement of the sections on which the letters are printed.

15 Section bearing numerals may be used in a similar manner to form numbers or sums or by providing the sections with other symbols or markings, pictures or ornamental and fanciful designs may be produced by the proper arrangement of the sections in either predetermined or arbitrary relation.

In Figure 6 has been shown a number of sections arranged and interlocked to form 25 two squares at right angles to each other, the squares being interwoven so that they form conjointly a complete article, the parts of which are integrally connected.

An article of this kind may be used for 30 ornamental purposes or it may have a useful object, it being apparent that in the manner shown doilies, mats and other similar objects may be constructed in a large variety of designs.

35 By connecting the end sections of a succession of sections as shown in Figure 1, a picture frame or napkin ring may be constructed, or by an arrangement of different parts each composed of a plurality of the 40 sections and interlocked by inserting the protruding corners of their end or edge sections through each other's slits, baskets, lamp shades and other devices too numerous to be separately mentioned, may be produced.

Now referring to the form of the invention illustrated in Figures 3 and 4, the sections each have one or more pairs of slits 6 extending obliquely in opposite directions 50 from an intermediate point in the perimetric edge of the article.

The slits of each pair may meet on the edge of the section as in the form shown in Figure 3 or they may be separate from each 55 other by an intermediate portion of said edge as indicated in Figure 11.

The double slits which preferably are formed at opposite edges of the section permit of a still larger variety of designs in 60 assembling the sections and by inserting portions of one section through both slits at one side of another section, the sections may be interwoven into an article of great rigidity.

65 As stated hereinbefore, the designs and

articles that can be made are innumerable, the articles produced may be ornamental only and used for decorative purposes or they may be useful as well as ornamental, thereby placing the invention in a class outside of that relating merely to educational appliances. However, it is as a medium of instruction that my invention is of particular value since it develops and stimulates the faculties or artistic conception and constructive ingenuity as a natural adjunct to a pleasurable occupation and without perceptible effort on the part of the student. 70

Having thus described my invention, what I claim and desire to secure by Letters Patent is:

1. A device for sectional construction comprising normally loose and separated pieces of pliable material slotted at and obliquely to their perimetric edges, for their interlocking connection. 75

2. A device for sectional construction comprising normally loose and separated pieces of pliable material slotted in opposite directions relative to intermediate points in their perimetric edges for their interlocking connection. 90

3. A device for sectional construction comprising normally loose and separated pieces of pliable material each having oppositely disposed slits at and obliquely to its perimetric edges, for their interlocking connection. 95

4. A device for sectional construction comprising normally loose and separated pieces of pliable material each having oppositely disposed pairs of slits for their interlocking connection, the slits of each pair diverging relative to an intermediate point in the perimetric edge of the respective piece. 100

5. As a new article of manufacture for sectional construction, a piece of pliable material having a pair of slits diverging obliquely from a common point in its perimetric edge. 105

6. A device for sectional construction comprising normally loose and separated geometrically formed pieces of pliable material slotted at and obliquely to their perimetric edges for their interlocking connection. 110

7. As a new article of manufacture for sectional construction, a normally loose piece of pliable material, perimetrically square, slotted at and obliquely to an edge thereof for its interlocking connection with another similar piece. 115

8. As a new article of manufacture for sectional construction, a normally loose piece of pliable material, perimetrically square, slotted at and obliquely to opposite edges thereof for its interlocking connection with other similar pieces. 120

9. As a new article of manufacture for sectional construction, a normally loose piece of pliable material, perimetrically square 125

and having at one edge, a pair of diverging slits for its interlocking connection with another similar piece.

10. As a new article of manufacture for 5 sectional construction, a normally loose piece of pliable material, perimetrically square, and having at opposite edges, pairs of diverging slits for its interlocking connection with other similar pieces.

10 11. An article of sectional construction composed of normally loose and separated sections slitted at and obliquely to their

perimetric edges and interlocked by insertion of a part of one section through a slit of another section.

12. An article of sectional construction composed of normally loose and separated sections having pairs of diverging slits at their peripheral edges and interwoven by insertion of a part of one section through 20 a pair of slits of another section.

In testimony whereof I have affixed my signature.

RAYMOND L. KURTZ.
